MACHINE FOR CLEANING BOTTLES

Ralph Waldo Webster, Waltham Cross, England

Application July 21, 1932, Serial No. 623,842, and
in Great Britain August 7, 1931

3 Claims. (Cl. 141—7)

This invention relates to machines for cleaning bottles in which bottles are soaked and washed while carried on an endless bottle conveyor and has for its object to provide means for more completely and efficiently rinsing the bottles. In such machines the bottles are generally submitted to a preliminary cleansing by passing them through one or more tanks containing a cleansing solution and are finally conveyed in an inverted position over a series of vertically reciprocating rinser tubes whereby the interior of the bottles is sprayed and rinsed, the rinser tubes being sometimes employed in conjunction with brushes for cleansing the inside and outside of the bottles. In many bottle cleaning machines the bottles and bottle holders are rotated while being sprayed, in some machines the spraying tubes are in fixed relationship to the frame of the machine on which the bottle holders are mounted, and in other machines the rinser tubes are advanced into and withdrawn from the interior of the bottles while being sprayed. The present invention relates to a simplified mechanism whereby the bottles while inverted and held stationary in the machine are subjected to a series of upwardly and outwardly directed jets of cleansing fluid while the rinser tubes are being advanced upwardly into the interior of the bottles, and to a series of downwardly and outwardly directed jets while the rinser tubes are being withdrawn from the bottles. Each rinser tube consists of an inner and an outer tube arranged concentrically and united at their upper ends by a ferrule. The top of the ferrule is pierced by a number of orifices in communication with the top of the inner tube, said orifices being directed upwardly and some of them outwardly and upwardly. Immediately below the ferrule the outer tube is pierced by a circumferential row of orifices directed downwardly and outwardly. The outward component of the direction of said orifices is for the purpose of imparting a swirling motion of the cleansing fluid along the interior surfaces of the bottles whereby every point thereof is effectively washed. The bottoms of the inner tubes are rigidly but adjustably connected to a lower fluid supply chamber, and the bottoms of the outer tubes to an upper fluid supply chamber, so as to suit bottles of varying sizes. Means are provided to admit cleansing fluid under pressure to the lower supply chamber and the inner tubes connected thereto, and to shut off the cleansing fluid from the upper supply chamber and outer tubes connected thereto, while the rinser tubes are being advanced into

the bottles and conversely while the rinser tubes are being withdrawn. By such means any dirt released from the walls of the bottles is effectively washed down and escapes from the mouths of the bottles.

Double rinser tubes are known each comprising inner and outer tubes connected respectively to two fluid supply chambers, and the present invention does not claim such double rinser tubes per se, but only in combination with the apparatus herein described.

But in order that the nature of the present invention may be more clearly understood and the same carried into practice reference may now be made to the accompanying drawings in which similar reference characters relate to like parts in all the figures and in which:—

Figure 1 is an elevation, mainly in section, of one of the double rinser tubes showing the connection of each tube to its respective supply chamber.

Figure 2 is a sectional plan on the line A—B Figure 1.

Figures 3 to 6 are views showing the action of the rinser tubes on their upward and downward travel.

Figure 7 is a view, somewhat diagrammatic, at right angles to the row of rinser tubes *r*, to show one method of operating the valves controlling the supply to the rinser tubes.

The construction of the rinser tubes will be apparent from Figures 1 and 2 of these drawings. Each consists of an inner tube *a* and an outer tube *b*, arranged concentrically. The inner tube *a* extends downwardly into its supply chamber *c* while the outer enclosing tube *b* extends only as far as the upper chamber *d* into which it depends as shown.

The tubes *a* and *b* are conveniently united at their upper ends by the ferrule *e*, the outer tube *b* being screwed or otherwise affixed to this ferrule while the inner tube *a* enters a bore *f* in the ferrule *e* and is swaged therein. The upper end of this bore *f* communicates with the orifices *g* in the ferrule *e* which forms a nozzle for the passage of the fluid under pressure admitted to the inner tube *a* from the chamber *c* and projected through the orifices *g* in the form of upward jets.

Immediately below the ferrule *f* downwardly inclined slots *h* are provided in the wall of the outer tube *b* whereby the fluid under pressure admitted to the tube *b* from the chamber *d* is projected through the slots *h* in the form of downwardly directed jets.

The action of these upwardly and downwardly directed jets will be more clearly appreciated on referring to Figures 3 to 6 it being understood that the tubes *a* and *b* with their respective supply chambers *c* and *d* are mounted on the tube carrier which with the fluid container is vertically reciprocated in the usual manner, the fluid under pressure being admitted by suitable valves opened and closed in any convenient manner, the opening and closing being timed to synchronize with the mechanism raising and lowering the tubes *a* and *b*.

Fluid under pressure is admitted to chamber *c* on the upward travel of the tubes *a* and *b* as the tubes enter the bottle neck (Figure 3) and the fluid thus admitted to tube *a* issues in upwardly directed jets through the orifices *g* and these upward jets are directed on to the interior surface and end of the bottle during the whole of the upward stroke. When the tubes have reached the limit of their upward travel at which point the force of the jets is directed on to the bottom of the bottle (Figure 4) and commence to descend the valve controlling the supply to chamber *c* is closed and the valve controlling the supply to chamber *d* is opened (Figure 5) whereby fluid under pressure enters the outer tube *b* and plays in downwardly directed jets through the orifices *h* on to the interior of the bottle during the whole of the downward stroke of the tubes and the valve is not closed to cut off the supply to the outer tube *b* until the tubes are withdrawing from the bottle (Figure 6), thus the dirt dislodged by the upward jets is effectively washed from the bottle neck.

A convenient method of operating the valves controlling the supply to the chambers *c* and *d* is shown in Figure 7.

The weighted and pivoted lever *k* is attached by the link *m* to the tube carrier *n* and is operated to raise and lower the carrier through the rod *o* adjustably secured to the eccentric rod *p* carried on the wheel *q*.

As the carrier *n* with the rinser tubes represented at *r* starts on its upward travel and the tubes enter the neck of the bottle *s*, a pawl *t* pivotally mounted on the carrier *n* strikes the pin *u* on the lever *v* that is pivotally mounted on the stub pin *w* and connected by rod *x* to the valve *y* controlling the supply to the chamber *c* (Figure 1). The lever *v* is thereby rotated and through rod *x* opens valve *y* whereby fluid under pressure passes to the tube *a*. When the tubes have reached the limit of their upward travel and are about to descend the adjustable striker bar *z* comes into contact with the pin *2* on lever *v* which returns the lever *v* to its original position thus closing the valve *y* through the rod *x*. Practically simultaneously the striker bar *z* contacts with the pin *3* on lever *4* that is pivotally mounted on the stub pin *5* and connected by rod *6* to the valve *7* controlling the supply to the chamber *d* (Figure 1). The lever *4* is thereby rotated and through rod *6* opens valve *7* whereby fluid under pressure passes to the outer tube *b*.

When the tubes are about to leave the bottles the striker *8* contacts with the pin *9* on the lever *4* thereby returning the lever to its original position and closing the valve *7* through the rod *6*.

It will be understood that the pawl *t* is mounted so as to swing freely on its pivot but on the up-

ward travel of the carrier *n* downward movement of the pawl *t* is prevented by the stop *10* so that on striking the pin *u* it rotates the lever *v* while on the downward travel the pawl *t* on striking the pin is merely swung upwardly and does not move the lever *v*. This lever *v* is returned to its original position as previously described by the striker bar *z* contacting with the pin *2* the bar *z* then reaching the top of its stroke and any further movement of the lever *v* is in any case prevented by the stop *11*. Similarly and practically simultaneously the lever *4* is rotated to open the valve *7* by the bar *z* striking the pin *3* and the lever *4* is returned to its normal position abutting the stop *12* by the lower end of the descending striker bar *8* striking the pin *9*.

What I claim is:—

1. In machines for cleaning bottles, a rinser member consisting of an inner and an outer tube arranged concentrically, a ferrule uniting the tops of said tubes and having upwardly directed orifices through the top thereof in communication with the top of the inner tube, the outer tube having a row of downwardly and outwardly directed passages immediately below said ferrule, an upper and lower fluid supply chamber to which the bottoms of the outer and inner tubes are respectively connected, means for vertically reciprocating said rinser tubes and fluid supply chambers, and means for admitting fluid under pressure to the inner tube during the upward travel of the rinser tubes and for admitting fluid under pressure to the outer tube during the downward travel of the rinser tubes.

2. In machines for cleaning bottles, a rinser member consisting of an inner and an outer tube arranged concentrically, a ferrule uniting the tops of said tubes and having upwardly directed orifices through the top thereof in communication with the top of the inner tube, the outer tube having a row of downwardly and outwardly directed passages immediately below said ferrule, an upper and a lower fluid supply chamber to which the bottoms of the outer and inner tubes are respectively connected, means for vertically reciprocating said rinser tubes and fluid supply chambers, and valve means for admitting fluid under pressure to the inner tube during the upward travel of the rinser tubes and for admitting fluid under pressure to the outer tube during the downward travel of the rinser tubes, and operating means operated by, and in synchronism with, the means for reciprocating the rinser tubes for operating the valve means.

3. In machines for cleaning bottles, a rinser member including spraying means for subjecting the interior of the bottle to upwardly and upwardly and outwardly directed jets of cleaning fluid, a second spraying means for subjecting the interior of the bottle to downwardly and outwardly directed jets of cleaning fluid, actuating means for advancing the rinser member into a bottle and withdrawing the rinser member from the bottle, and means for admitting fluid under pressure to the first spraying means during the movement of the rinser member into the bottle and for admitting fluid under pressure to the second spraying means during the movement of the rinser member from the bottle.

RALPH WALDO WEBSTER.
